United States Patent Office.

CHARLES W. FERGUSON, OF JACKSON, TENNESSEE.

Letters Patent No. 102,794, dated May 10, 1870.

IMPROVEMENT IN BRICK-MACHINES.

The Schedule referred to in these Letters Patent and making part of the same.

I, CHARLES W. FURGUSON, of Jackson, Madison county, Tennessee, have invented a new and useful Brick-Machine, of which the following is a specification.

Nature and Objects of the Invention.

My invention comprises certain devices for drawing the pulverized and tempered clay from the pug-mill down an inclined plane, and for feeding it into the molds, the construction being such as to permit the escape back onto the inclined plane of the superfluous clay.

It also comprises a construction of molds, whose top and two sides are movable, by which means the clay is first pressed with great force, so as to completely fill the mold, and the completed brick is readily expelled therefrom.

General Description with Reference to the Drawings.

Figure 1 is a side elevation of a machine embodying my invention.

Figure 2 is a longitudinal section with the parts in position to commence the formation of a brick.

Figure 3 is an end view of the machine.

Figure 4 is a longitudinal section of the parts constituting the mold in the positions they assume at the completion of a brick.

Figure 5 is a perspective view of the same parts, without the sliding gate, and with the vertical and horizontal plungers retracted.

Secured to the frame A of the machine is a shaft, B, having a spur-wheel, C, and being operated by a band passing around a pulley, b.

The wheel C communicates motion, by the pinion c, to the shaft D of a pug-mill, F, within which the said shaft, with its arms d and blades E, revolves, an aperture, f, in the side of the pug-mill conducting the tempered clay onto an inclined plane or chute, R, down which the clay is made to pass to the molds, in the manner hereafter described.

A bevel-wheel, V, on shaft B, gears with a pinion, G, on the shaft g, and this shaft is provided with a crank, g', and pitman, H, which actuate the pressing-plunger I, the latter operating on the top of the clay contained in the mold J, which mold is divided into a series of compartments by vertical partitions j, so as to permit of a number of bricks being pressed at the same time.

The pressing-plunger I is provided with a number of openings, i, which coincide with the partitions j of the mold J.

The front of the mold is a sliding gate, K, which, at the proper time, is elevated by the cam g" on the shaft g.

The back of the mold is a horizontally-sliding plunger, L, having a rack, l, which gears with a segment-wheel, M, or a rock-shaft, m.

The gate K descends by its own weight, and is confined to a vertical path by guides k k'.

The rock-shaft m is vibrated at the proper moment by the rods N N', operated by studs o p, that project from the wheels O P.

The molds J are supplied with clay in the following manner:

R is an inclined plane or chute which reaches from the molds up to the bottom of the pug-mill F, and is provided with a scraper, S, which draws the clay down the incline to the mouth of the mold.

The scraper S has a reciprocating movement imparted to it by the connecting rods s s', which are attached to cranks or wrists t t' of the shaft T.

The wheels O P U are driven from bevel-wheel V by means of a bevel-pinion, W, secured to the inner side of wheel O.

Operation.

The gate K being in its depressed or closed position, the plunger I being elevated and the plunger L retracted, the follower or scraper S is supplying the mold J with clay, (see fig. 2).

The rotation of the crank g' meanwhile causes the plunger I to descend, thereby compressing the clay in the molds.

This is followed by an elevation of the gate K and a further advance of the plunger L, so as to expel the bricks from the mold, and to deliver them onto the table X.

The plunger L is now retracted, the plunger I elevated, the gate K closed, and the mold thus made ready for another charge of clay.

Claims.

I claim herein as new and of my invention—

1. The described arrangement of pug-mill D d, inclined plane R, scraper S, pressing-plunger I, and gate K, for the purposes set forth.

2. The combination of the plungers I and L, gate K, scraper S, and inclined plane R, for the purpose of feeding, compressing, and discharging the contents of the mold J, in the manner set forth.

3. In combination with the elements I, K, and L, the rack l, segment-wheel M, rock-shaft m, rods N N', and studs o p, for actuating the expelling-plunger.

In testimony of which invention I hereunto set my hand.

CHARLES W. FERGUSON.

Witnesses:

GEO. H. KNIGHT,
JNO. E. GLASS.
